UNITED STATES PATENT OFFICE

RUFUS LOOSE SPAYD, JR., OF NORTH GLENSIDE, PENNSYLVANIA

CASTER SOCKET

Application filed June 19, 1931. Serial No. 545,545.

My present invention has reference to furniture casters and has for its object to provide a simple economical means for vertically adjusting the caster to compensate for variations in the lengths of furniture legs, whereby such furniture can be micro-metrically leveled.

Another object of the invention is the provision of means for holding the caster steady 10 in the adjustable member.

With the above and other objects in view the invention consists in certain peculiarities in construction and combination of parts which will hereinafter be set forth with particularity in the accompanying drawing and specifically pointed out in the appended 15 claim.

In the drawing:

Figure 1 is a side elevation of the improvement in applied position, the leg for the furniture being in section.

Figure 2 is a side elevation of the socket and the adjustable element therein in section.

Figure 3 is a similar view showing the sleeve as well as the fixed socket in section.

Figure 4 is a view of the adjustable element.

Referring to the drawing in detail, the numeral 1 designates the leg of any desired article of furniture, and let in the leg from the bottom thereof there is the tubular member that comprises the socket 2 of the improvement. The socket has its lower or outer 30 end flanged, as at 3, and the said flanges provided with openings for the reception of securing means, such as screws, that enter the bottom of the leg 1. The socket 2 is interiorly threaded throughout its length. Threaded 35 for vertical adjustment in the socket 2 there is a stop member 4. The stop member may have both of its opposite faces kerfed, as at 5, for the reception of the bit of a screw driver whereby the stop member 4 may be properly 40 adjusted in the socket 2. The caster is indicated by the numeral 6 and the shank or stem therefor by the numeral 7. The outer end of the stem 7 is enlarged or headed to provide the same with an inner shoulder 8.

The numeral 9 designates the adjustable

member of the improvement. The member 9 is in the nature of a tubular sleeve and receives in the bore thereof the stem 7. The outer end of the sleeve 9 is formed with an outstanding flange 10. When it is found desirable to prevent the caster wheel from turning, the flange 10 is provided on its outer face with V-shaped notches 11 to receive therein cross sectionally V-shaped lugs 12 on the caster at the juncture of the shank 7. 55 The sleeve 9 is exteriorly threaded, as at 13, throughout its length. The inner end of the sleeve is closed, but the said sleeve, from its said closed end, is cut away at points adjacent to its sides to provide the same with a central reduced extension 14 and with fingers 15 which are disposed below the top of the central extension 14. The side walls provided by the fingers are cut at opposite angles, as disclosed by the drawing, so that the outer ends of the fingers are materially reduced which renders the fingers readily susceptible to bending. These fingers, after 60 the stem 7 of the caster 6 is received through the sleeve are bent inwardly to contact with the shoulder 8 of the stem 7 and whereby the sleeve 9 is rotatably supported but held from longitudinal movement on the stem 7, when the interengaging lugs 12 and notches 11 65 are not employed. After the distance between the floor and the socket has been obtained the stop element 4 is adjusted in the socket so that the same will be in position to be contacted by the inner closed end of the sleeve 9 when the same is screwed in the 70 socket. This adjustment may be obtained before the socket is inserted in the leg of the furniture if desired, and the adjustment of the caster can be readily made by any one without resorting to a skilled mechanic, and 75 when so adjusted the tension between the parts will hold the caster in properly adjusted position.

It is thought from the foregoing description the novel features of my invention will 80 be readily apparent but it is to be understood that I do not wish to be restricted to the precise details of construction herein set forth and may make changes in the construction and combination and arrangement 85 90 95 100

of the several parts providing such changes fall within the scope of what I claim.

Having described the invention, I claim:

- A caster mounting including a caster stem
5 having an enlargement at one end to form an annular shoulder, an exteriorly threaded sleeve mounted on the stem and having a closed end with the enlargement of the stem in abutting engagement therewith, said
10 sleeve having cut-out portions in opposite walls adjacent the closed end to provide fingers bendable to engage the annular shoulder for cooperating with the closed end in rotatably securing the sleeve to the stem, a
15 flange on said sleeve and having notches, teeth on the stem to ride into and out of the notches during rotation of the sleeve on the stem, an internally threaded anchoring sleeve having the first sleeve threaded therein, and a stop for limiting the threading of the first sleeve into the anchoring sleeve and threaded in the latter to vary its location
20 within said anchoring sleeve.

In testimony whereof I affix my signature.
